Filed June 16, 1958, Ser. No. 51,387

Term of patent 14 years

(Cl. D91—1)

Fig. 1 is a top plan view of a sprinkler showing our new design;

Fig. 2 is an enlarged fragmentary side elevational view thereof; and

Fig. 3 is a fragmentary view looking in the direction of the arrows 3—3 of Fig. 1 showing the opposite side of the arm member shown in Fig. 2.

The dominant features of our design reside in the portions shown in full lines.

What we claim is:

The ornamental design for a sprinkler, substantially as shown and described.
